Primary Examiner — George J Ulsh*Assistant Examiner* — Bethany Louise Mallino(74) *Attorney, Agent, or Firm* — Squire Patent Consulting & IP Law LLC; Brendan E. Squire(57) **CLAIM**

The ornamental design for a power equipment cover as shown and described.

DESCRIPTION

FIG. 1 is a front perspective view of the power equipment cover showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is perspective view showing the power equipment cover in use and with part of an implement shown in phantom.

The broken lines in FIG. 8 showing the power equipment cover in use illustrate environment and form no part of the claim.

The dash-dot-dash line of FIG. 7 illustrates a boundary that forms no part of the claim.

1 Claim, 4 Drawing Sheets(56)
